CLAIM

The ornamental design for a combined snow shovel and pusher, as shown and described.

DESCRIPTION

FIG. 1 is a perspective view of a combined snow shovel and pusher showing my new design, the broken-line showing of the portion of a handle being for illustrative purposes only, and forming no part of the claimed design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a left side elevational view thereof, the right side being a mirror image thereof.

FIG. 1

FIG. 2

FIG. 3

FIG. 6

FIG. 4

FIG. 5
